UNITED STATES PATENT OFFICE.

MAXIMILIAN WEIL, OF NEW YORK, N. Y.

RECEIVER.

1,321,171.

Specification of Letters Patent. Patented Nov. 11, 1919.

Application filed April 4, 1917, Serial No. 159,780. Renewed April 3, 1919. Serial No. 287,348.

To all whom it may concern:

Be it known that I, MAXIMILIAN WEIL, a citizen of the United States of America, residing at borough of Manhattan, city, county, and State of New York, have invented certain new and useful Improvements in Receivers, of which the following is a specification.

This invention relates to receivers and particularly to aural receivers for electrical, acoustic and other communicating instruments.

In certain preferred forms, the invention comprises a pair of complementary receivers adapted to be individually used with the respective ears of the user and means for combining said individual receivers into a resultant single receiver adapted to be used with one ear only of the user, similar to the usual telephone receiver.

Such preferred form of the invention comprises a pair of substantially semi-cylindrical receivers constructed to be individually connected with the communication system, each said receiver having on its non-circular face a depressed receiving passage adapted to be brought into communication with the opening of the ear and means for attaching said receivers to one another to form a single receiver having a resultant substantially cylindrical form similar to the common telephone receiver, said depressed passages forming a common internal passage of the resultant single receiver leading to the exterior thereof and adapted to be brought into communication with the opening of an ear of the user. The duplex-unitary acoustic receiver form of the invention is also applicable for use with an electrical telephone in coaction with suitable acoustic receiving means adapted to be placed either temporarily or continuously in operative relation to the electrical telephone receiver, in which latter instance the duplex-unitary acoustic receiver, when not in use may be placed on the receiver hook to break the speaking circuit connection.

Further features and objects of the invention will be understood from the following detail description and the accompanying drawings, in which—

Figures 1 and 2 are respectively side and front elevations of an embodiment of the invention, showing a base for supporting an electrical telephone; Fig. 3 is a top plan view of the base of the aforesaid figures;

Fig. 4 is a central longitudinal section of my duplex acoustic receiver's connected together as a single receiver;

Fig. 5 is a side elevation of one of said single acoustic receivers;

Fig. 6 is a transverse section on line 6—6 of Fig. 4;

Fig. 7 is a diagrammatic view showing the invention in use with both ears of the user;

Fig. 8 is a central longitudinal section of my duplex electrical receivers connected together as a single receiver;

Fig. 9 is a side elevation of one of said single electrical receivers;

Fig. 10 is a diagram of the preferred electrical connections of the electrical parts of Figs. 8 and 9.

Referring to Figs. 1, 2 and 3, the electrical telephone 1, such as the desk set type, is preferably provided with a base 2 having the depressed portion 3 for receiving the base 4 of the telephone 1. The electrical telephone receiver 5 may also be supported on base 2 by means of the bracket 6 constructed in proper relation to the acoustic receiving means 7, shown also as supported by the bracket 8 on the base 2.

Said receiving means 7 is acoustically connected by the communicating passage 9 with the acoustic receiver 10.

The duplex acoustic receiver 10 comprises the complementary separate receivers 11, 12, respectively connected to the communication passage 9 by separate passages 13, 14, respectively joined with said communication passage 9 by means of the Y connector 15.

Said receiving means 7 is of any suitable construction and provided with the receiving passage 16 communicating by the nipple 17 with the tubing 9.

The base 3 as constructed is preferred in view of the advantages of supporting in common the electrical telephone, receiver 100 rest and the receiving means, although certain objects of the invention will be attained by other related supporting means.

Said duplex-unitary acoustic receiver is shown in greater detail in Figs. 4, 5 and 6. In Fig. 4, showing both receivers connected as a single receiver, the aural passage 20 of receiver 11 communicates with the tubing 13; similarly, the aural passage 21 of individual receiver 12 communicates with the tubing 14.

As shown also in Fig. 5, said passage 20

preferably leads to the exterior opening 22 shown as a recess depressed on the non-cylindrical face of receiver 11. Said aural opening 22 communicates through the passage 23 with the frontal aural opening 24. Similarly said aural passage 21 of individual receiver 12 communicates with the depressed aural opening 25 leading also through said passage 23 to said frontal aural opening 24.

10 The specific means of combining the pair of individual receivers 11, 12, is shown in the form of the tongue 27 carried by receiver 11 on its non-cylindrical face and the groove 28 disposed in the non-cylindrical face of receiver 12, said tongue 27 being insertible within said groove 28 and the said individual receivers 11, 12 connected as a single receiver by relatively sliding movement.

In Fig. 7 I have shown the individual receivers 11, 12, applied to the two ears of the user, said receivers being connected through the receiver tubing 13, 14 with the main tubing.

It will also be clear from Fig. 7 that my duplex receivers are applicable for use in an acoustic communication line, the said tubing 9 serving as the receiving line of the acoustic system to which the acoustic transmitter is connected.

30 In Figs. 8 and 9 I have illustrated the form of my duplex receiver for use in an electrical telephone system. Said duplex receiver comprises the individual receivers 30, 31 connected or combined with one another by means of the tongue 32 and groove 33. In receiver 31 I have provided the electro-magnet 34 having a pair of coils 35 disposed at the poles thereof arranged in operative relation to the diaphragm 36 of magnetic material as will be understood by the art. Similarly, in individual receiver 31 I have provided the electro-magnet 37 having the pair of coils 38 disposed at the poles thereof arranged in suitable relation to the diaphragm 39 of magnetic material as will be understood by those skilled in the art. The pair of terminals 40 connected to the ends of coils 35 are suitably connected in the line and the pair of terminals 41 connected respectively to the ends of the wiring of coils 38 are suitably connected in a similar manner in the telephone line.

The aural opening 42 of receiver 30 is adapted to be placed in communication with the opening of an ear of the user and similarly the aural opening 43 of receiver 31, when the individual receivers are applied to the two ears of the user. Said aural openings 42, 43, when said individual receivers 30, 31, are combined as a single receiver, are related to one another to provide a common unitary passage communicating with the frontal aural opening 44 of the resultant single receiver.

65 In Fig. 10 I have indicated one form of

connection of the coils 35, 35 of receiver 30 and the coils 38, 38 of receiver 31, with the receiving wiring 45, 46, as will be understood from those skilled in the art.

It will be understood that the individual 70 receivers may be of other resultant shape than substantially cylindrical, the said illustrated shape being advantageous to provide an acoustic or electrical receiver capable of use with the common types of telephone. 75

It will also be noted that the arrangement of aural opening in both the acoustic and electrical forms of my invention may be modified as circumstances will suggest, consistent with attaining the objects of the in- 80 vention.

Whereas I have illustrated and described my invention by reference to specific forms thereof, it will be understood that many changes and modifications may be made 85 therein without departing from the invention.

I claim.

1. The combination of a plurality of aural receivers and means for connecting said receivers together to form a single aural receiver. 90

2. The combination of a plurality of aural receivers and means for holding said receivers together to form a single aural receiver. 95

3. The combination of a plurality of aural receivers and means for combining said receivers together to form a single aural receiver. 100

4. The combination of a plurality of aural receivers, each having a receiving opening and means for attaching said receivers together to provide a common opening communicating with said openings. 105

5. The combination of a plurality of complementary aural receivers, each receiver having a passage extending to an outer face thereof and means for combining said receivers together to provide a common passage 110 communicating with said passages.

6. The combination of a plurality of aural receivers having complementary faces and individual receiving means in each of said receivers. 115

7. The combination of a plurality of aural receivers, each receiver having individual receiving means, said receivers having complementary faces and means for connecting said receivers unitarily. 120

8. The combination with a communication line, of a plurality of receivers, each receiver having individual receiving means, means for connecting said individual receiving means with the line and said receivers having complementary parts whereby said plurality of receivers are capable of being assembled as a resultant single receiver. 125

9. The combination of a plurality of receivers, individual receiving means in each 130

of said receivers and means for combining said receivers together to form a resultant single receiver.

10. The combination of a plurality of receivers, each receiver having individual receiving means, and means for combining said receivers into a single receiver, said resultant single receiver having a single aural opening.

10 11. The combination of receivers each receiver having individual receiving means and individual aural openings and means for combining said receivers into a resultant single receiver having a single aural opening.

15

12. The combination of a plurality of receivers each receiver having individual receiving means and an aural opening on a side face and means for combining said receivers into a resultant single receiver having an aural opening on a front face.

13. The combination of a plurality of receivers each receiver having individual receiving means, means connecting said receiving means together, said receivers having aural openings on complementary faces thereof, and means for placing said receivers.

In testimony whereof I have signed this specification this 27th day of March 1917.

MAXIMILIAN WEIL.
